In Great Britain February 20, 1932

8 Claims. (Cl. 181—31)

This invention relates to instruments of the electro-dynamic or moving-coil type for use in the reproduction of sound, that is to say for use for producing sound from electric current of audio-frequency or for producing audio-frequency electric currents from sound waves.

There are in common use two main classes of loud speaking instruments of the type in question for producing sound waves from audio-frequency current, namely the horn type, in which a small vibratory diaphragm serves to energize an air column contained within a horn, and the large diaphragm type, in which a comparatively large diaphragm, usually of conical formation, acts in conjunction with a "baffle-board" to impart vibratory movement to the surrounding air. With a view to economy in the magnet employed in a moving-coil loud speaker, it is desirable that the annular gap thereof should be of the smallest possible radial dimensions, and little or no difficulty is encountered in this direction in the case of the small diaphragms which work in conjunction with a horn. Considerably greater difficulty, however, is encountered in connection with large diaphragm type loud speakers, because, for the same loudness level of reproduced sound, without a horn, the amplitude of the vibrations even of a large diaphragm, must be greater than where a horn is employed. Small loud speakers intended for domestic use are almost invariably of the large diaphragm type in view of the large amount of room taken by an adequate horn, and it is in such loud speakers that it is particularly important for reasons of cost to employ magnets having annular gaps of small radial width. In such loud speakers, many different arrangements have been proposed for maintaining the moving-coil properly central and in proper alignment in the annular gap of its associated magnet. Various electro-dynamic or moving-coil instruments for use in the production of audio-frequency electric current from sound waves are also known already.

The present invention has for an object to provide improvements in electro-dynamic or moving-coil microphone or sound reproducing instruments.

For use in the reproduction, or recording, of sound waves, it has already been proposed to provide in combination, and, inter alia, for application to the known moving coil type of instrument, a vibratory flat or disc diaphragm of thin sheet metal and a hollow truncated cone, the smaller end of which is secured to the flat vibratory diaphragm along a circular or annular

region of the latter that is inset from the outer periphery of the free vibratory portion thereof.

According to the present invention, however, a composite diaphragm, for use in an instrument of the kind referred to comprises two elements, the one being formed from sheet metal as a flanged dome and having the former of the moving coil attached thereto as by adhesive so that the moving coil extends coaxially thereof at the junction of the dome with the flange; and the other being of conical formation and coaxially attached as by adhesive at its smaller periphery to the convex surface of the dome.

The invention is illustrated by the accompanying drawings, of which

Figure 1 shows in half sectional side elevation, a loud speaker according to one form of the invention, part of the magnet thereof being broken away; and

Figure 2 is a fragmentary section view of an alternative arrangement of loud speaker; whilst

Figure 3 shows a microphone in part sectional side elevation.

As shown in Figure 1, a loud speaker comprises, apart from the vibratory diaphragm, a magnet, indicated at 11, having an annular gap, indicated at 12, of small radial width, and a centre pole piece 13, and a conical support 14 for the vibratory diaphragm. The diaphragm comprises a conical element 15, similar to that of the large diaphragm 85 loud speaker, formed from paper in the well-known manner, but without a flange at its larger periphery, to which is secured, as by adhesive, a surround 16 of flexible material, such for example, as thin leather, and a smaller, comparatively rigid 90 element, like the diaphragm of a horn type loud speaker, formed by pressing from thin sheet metal or metallic alloy, with a central domed portion 17 and with a wide flange 18 formed with concentric corrugations 19; the two elements of the 95 diaphragm as a whole being secured co-axially together, as by adhesive, as indicated at 20, at the smaller end of the conical element 15. The moving coil, indicated at 21, is wound on a thin paper former, 22, the upper margin of which is 100 serrated, and secured by adhesive to the smaller diaphragm element, as at 23, at the junction of the domed portion 17, with the flange 18 thereof. The two diaphragm elements 15 and 17, 18 and the moving coil 21, are disposed co-axially of one 105 another. The conical support 14 is formed at its smaller end with an apertured inturned flange 24 and with a further angle section flange 25 at its larger periphery, and also with the usual openings, indicated at 26; whilst an annular clamping 110

member 27 of channel section and lined with felt 28, is secured by screws, one of which is indicated at 29, to the flange 25 of the support 14.

In the production of a loud speaker such as

- 5 that indicated in Figure 1, the smaller diaphragm element 17, 18 is first formed as above mentioned, by pressing from thin sheet metal, then the moving coil 21, already wound on its former 22, is secured to the smaller diaphragm element 10 17, 18 in the manner explained; an apertured washer 30 is placed on the magnet 11 so that apertures therein register with corresponding threaded bores, one of which is indicated at 31, in the magnet 11; then the small diaphragm element 15 and moving coil assembly is placed in position, with the moving coil 21 located in the gap 12 of the magnet 11, with apertures in the outer margin of the flange 18 in register with those of the washer 30 and of the magnet 11, two further 20 apertured washers being placed one below and one above the flange 18; then, the support 14 is placed in position with the apertures in its smaller flange 24 in register with those just mentioned, and all the apertures, with the exception of the 25 bores 31 of the magnet 11, being "over size." All these parts are secured firmly together by screws, of which one is indicated at 32, passed through the various apertures. The over size apertures in the flange 24 and in the surround 30 18 permit proper centering of the moving coil 21 in the gap 12 before the screws 32 are finally tightened, and once these are tightened, there is no possibility of the coil 21 or smaller diaphragm element 17, 18 becoming displaced laterally. Next, 35 the clamping member 27 and screws 29 being removed from position, the conical diaphragm element 15 is placed in position truly co-axial with the smaller diaphragm element 17, 18; the clamping ring 27 is secured in position by the screws 40 29, two washers being disposed, the one above, and the other below, the surround 16 of said element 15, and the inner end of the diaphragm element 15, which abuts against the domed portion 17 of the smaller diaphragm element 17, 45 18 is secured thereto by adhesive, as indicated at 20.

Leads (not shown) from the moving coil 21 may be brought out in any known or convenient manner to suitable terminals (not shown).

- 50 In the form shown in Figure 2, a similar magnet 41, support 42 and conical diaphragm 43, are employed. The smaller diaphragm element, however, in this case is formed by pressing with a domed portion 44 and with a flat flange 45 which 55 is not formed with corrugations. In this case also, a moving coil 46 is attached to the small diaphragm 44, 45 in the same way as in the case of Figure 1. The smaller diaphragm 44, 45 is further provided with a separate surround 47 of 60 comparatively flexible thin sheet material, such as celluloid, which is secured to the flange 45 of the smaller diaphragm element 44, 45 by adhesive. The outer margin of this surround 47 is mounted by means of screws, one of which is indicated at 48, passed through oversize holes in an inturned flange 49 of the support 42 through oversize holes in packing washers and in said surround 47 into threaded apertures, one of which is indicated at 49a, in the magnet 41. Proper centering 70 of the moving coil 46 is obtained in just the same way as in the Figure 1 arrangement. In this case, and in all cases where the smaller diaphragm element is provided with a separate surround, it is desirable that the latter, the flange of the 75 small diaphragm element to which it is secured,

and the manner in which these parts are secured together, should be such that during axial vibratory motion of the element, flexure will take place mainly at, or in the neighbourhood of, the inner edge of the surround, i. e. in the neighbourhood of the junction of the flange with the domed portion of the diaphragm. This may be attained by appropriately proportioning the flange of the smaller diaphragm element and the surround and suitably choosing the materials thereof.

It will be noted that in Figure 2, the moving coil 46 does not extend to what may be termed the inner end of the annular gap of the magnet 41.

In point of fact, the arrangement is such that neither the moving coil nor its former will over reach the end of the gap during normal use

of the instrument. In this case also the centre pole, indicated at 50, of the magnet 41 is of larger diameter below the gap than in the case of the

Figure 1 arrangement, and in the space between this enlarged part of the centre pole 50 and the annular pole of the magnet is placed a layer of

cotton wool, indicated at 51, which is retained loosely in position by a strap 52 of such material as adhesive tape. In this way, any possibility

of dust or small particles of metal entering the gap through its inner end is obviated. It will be noted that in all cases the outer end of the gap

is effectively sealed by the smaller diaphragm element against the ingress of such foreign material.

In all loudspeakers according to the invention, it is desirable that the larger circumference of the conical diaphragm element should be mounted freely, not only as regards axial motion, but also

as regards motion at any part thereof in a direction normal to that part, for it is found desirable not to restrain the tendency of the conical diaphragm element 15 to vibrate after the fashion of a bell at certain frequencies. It is for this reason that neither of the conical diaphragm elements shown in Figures 1 and 2 has a flange at its

larger circumference.

The microphone instrument shown in Figure 3 of the drawings is essentially similar to the loud speaker instruments just described except that

the magnet employed is somewhat, and the conical diaphragm element is considerably, smaller than in the case of the loud speakers.

As shown, a permanent magnet 61 is secured to a flanged circular base plate 62, and a domed, metal diaphragm element 63 having a moving-

coil 64 secured thereto as by adhesive is mounted upon the magnet by means of screws 65 and clamping rings 66, between which latter the flange

of the metal element 63 extends; the screws 65 passing through oversize holes in said flange so that proper centering of the moving coil 64 in the gap of the magnet 61 may readily be effected.

A light conical diaphragm element 67 is secured by adhesive as indicated at 68 at its smaller end to the central domed portion of the metal element 63 and the larger periphery of the element

67 is turned over to provide a flange 69, said element 67 having no surround and being supported solely by its attachment to the metal element 63.

The whole is enclosed by a cylindrical case 70 secured detachably at its lower end to the base plate 62 and formed at its upper end with a circular opening 71 similar in size to the larger

end of the conical element 67, which opening 71 is covered by loosely woven fabric or other material 72 which offers little or no impedance to sound waves.

One advantage of a composite diaphragm

according to the invention is that, by reason of the rigidity of the smaller diaphragm element and moving coil assembly, any pressure applied to the conical diaphragm element at one point in its larger periphery will simply result in inward movement of the smaller diaphragm element and moving-coil assembly as a whole, and not in any greater inward movement of the moving-coil at one side thereof than at the other. In other words, as it is carried by a comparatively rigid small diaphragm element, the moving-coil cannot be tilted in the gap by pressure applied unevenly to the conical diaphragm element as it could be if it were attached directly to a conical diaphragm element as is usual with known large diaphragm type sound reproducers or loud speakers. This property assists greatly in rendering possible the use of a magnet, the annular gap of which is of small radial width. It is found, for example, that once the small diaphragm element with the moving-coil thereon has been mounted correctly upon the magnet, and provided that the coil itself is clear of the pole pieces of the magnet, neither the actual attachment of the large conical dia-

phragm nor any forces which may later be applied to the latter can affect the proper location of the coil in the gap, and that a clearance of even two thousandths of an inch between the coil and the pole piece is quite sufficient.

It will be observed that the nearer to the centre of the small diaphragm element the large diaphragm element is attached thereto, the more effectively will any tendency of tilting the moving-coil as a result of uneven pressure upon the large diaphragm element be avoided.

Although in the case of a microphone no surround is actually necessary for the conical diaphragm, any known means for supporting the surrounds of the two diaphragm elements may be employed; for example, it may, in the case of some loud speakers, be desirable to employ an arrangement where the support 14 is attached to the magnet, independently of means which permit of proper centering of the moving-coil and whereby the surround of the smaller diaphragm element is clamped in position. This is very important where loud speakers have large and heavy magnets, although the use of such large magnets is less necessary in cases where a composite diaphragm according to the invention is employed than it is where diaphragms of the usual type are employed. It will be observed that whatever happens to the large conical diaphragm element, even if it be damaged severely, it is practically impossible for the moving-coil to be shifted laterally relatively to the magnet. It has, in fact, been found possible to employ successfully both in loud speakers and in microphones, magnet having a gap, the radial width of which is so small as thirty-five thousandths of an inch, thus enabling the use of a permanent magnet of so small a weight as four and a half pounds to provide an effective magnetic flux density for the moving-coil such as would, with known arrangements, have necessitated the use of a permanent magnet weighing so much as ten pounds.

Besides being very effective in obtaining faithful reproduction of sound, an instrument according to the present invention possesses the advantage that the employment of a small diaphragm as above described provides a very rigid support for the moving-coil, and thus obviates all risk of the coil losing shape and becoming distorted. Further, even when the magnet is

unenclosed, it is quite impossible for any foreign matter to pass from the inside of the cone between the moving-coil and the gap of the magnet, and the space between the moving-coil and the annular pole piece of the magnet and the inner end of the gap can easily be sealed, so that with the improved instrument there should be no risk of foreign matter entering the magnet gap and causing trouble, as is so often experienced with other instruments the moving-coils of which operate in the magnet gap with small clearance.

Thus, an instrument according to the invention, especially where a conical diaphragm element of paper is treated with a preservative, or where the conical element is of a material of a more permanent nature than paper, has a very long and useful life, during which it will remain very efficient in operation without requiring any attention or maintenance whatever, and, moreover, a loud speaker according to the invention is substantially immune from a wear or damage except in the unlikely event of its being grossly overloaded or handled very roughly indeed.

What we claim is:—

1. A composite diaphragm for use in an instrument of the kind referred to, comprising two elements, the one being a flanged dome having the former of the moving-coil attached thereto so that the moving-coil extends coaxially thereof at the junction of the dome with the flange, and the other being of conical formation and coaxially attached at its smaller periphery to the convex surface of the dome.

2. A composite diaphragm, as claimed in claim 1, wherein the one element has a surround incapable of yielding appreciably in a radial direction, and wherein the other conical element is capable of, and has a surround which permits, axial movement and also movement at any point of its larger peripheral margin in a direction other than axial.

3. A composite diaphragm as claimed in claim 1 wherein a flat margin of the one element is extended and formed with a plurality of concentric corrugations to constitute a surround.

4. A composite diaphragm as claimed in claim 1 wherein a flat margin of the one element has secured thereto a flat annulus of sheet material constituting a surround.

5. A composite diaphragm as claimed in claim 1, wherein a flat margin of the one element has secured thereto a flat annular of sheet material constituting a surround, the flat margin and the surround being such and being so secured together that during axial motion of said element, flexion will take place mostly at or in the neighbourhood of the inner edge of the surround.

6. A composite diaphragm for use in an instrument of the kind referred to comprising two elements, the one being a flanged dome having the former of the moving coil attached thereto so that the moving coil extends coaxially thereof at the junction of the dome with the flange, and provided with a surround incapable of yielding appreciably in a radial direction, and the other being of conical formation and coaxially attached at its smaller periphery to the convex surface of the dome and being capable of, and having a surround which permits, axial movement and also movement at any point of its larger peripheral margin in a direction other than axial, the dome having a flat, extended margin formed with a plurality of concentric corrugations to constitute a surround.

7. A composite diaphragm for use in an instrument of the kind referred to comprising two elements, the one being a flanged dome having the former of the moving coil attached thereto so that the moving coil extends coaxially thereof at the junction of the dome with the flange, and provided with a surround incapable of yielding appreciably in a radial direction, and the other being of conical formation and coaxially attached 5 to its smaller periphery to the convex surface of the dome and being capable of, and having a surround which permits, axial movement and also movement at any point of its larger peripheral margin in a direction other than axial, the 10 dome having a flat margin, and a flat annulus of sheet material secured to the flat margin, the flat annulus constituting a surround.

15 8. A composite diaphragm for use in an instrument of the kind referred to comprising two elements, the one being a flanged dome having the former of the moving coil attached thereto so

that the moving coil extends coaxially thereof at the junction of the dome with the flange, and provided with a surround incapable of yielding appreciably in a radial direction, and the other being of conical formation and coaxially attached at its smaller periphery to the convex surface of the dome and being capable of, and having a surround which permits, axial movement and also movement at any point of its larger peripheral margin in a direction other than axial, the dome having a flat margin, and a flat annulus of sheet material secured to the flat margin, the flat annulus constituting a surround, the flat margin and the surround being such and being so secured together that during axial motion of said element, flexion will take place mostly at or in the neighborhood of the inner edge of the surround.
